REARMING TOOL

Alfred H. Haberstump, Detroit, Mich., assignor to
 The Murray Corporation of America, Detroit,
 Mich., a corporation of Delaware

Application January 11, 1943, Serial No. 471,958

12 Claims. (Cl. 86—48)

This invention relates to re-arming tools and particularly to a re-arming tool for connecting or disconnecting cartridges to metal links which interlock with each other and the cartridges for forming an ammunition belt.

The tool is so constructed that, through the operation of a lever in one direction, a cartridge is inserted in the nested links with the projectile and cartridge ends in aligned relation to adjacent cartridges or, through the movement of the lever in the same direction, a cartridge may be withdrawn from the links, thereby separating the belt at that point. The tool embodies a receiver of channel section having upwardly projecting prongs at one end for receiving the nested links. A channel-shaped carriage having inwardly directed flanges at the front end is longitudinally movable within the receiver.

A lever is pivoted to the receiver having a slotted portion extending thereabove and therebelow, with a portion therebelow in position to be grasped by the hand of the operator. A downwardly extended handle portion is provided on the end opposite to that having the upwardly projecting prongs toward which the lever is moved by the operator. A link interconnects the lever and the longitudinally movable carriage. The pivot connecting the lever to the links is adjustable in the slot therein so that the end of the link may be positioned at the upper end of the lever above the receiver or may be moved to a position below the receiver. The link end is retained in either end of the slot by a toggle operating spring.

When the link is above the receiver, the movement of the lever toward the handle portion moves the carriage forwardly. When the link is below the receiver, the same movement of the lever toward the handle portion pulls the carriage to the rear. When the carriage is moved forwardly, the inwardly projected flanges of the carriage abut against the heel of the cartridge to force the cartridge forward into the links retained by the upwardly projecting prongs on the forward end of the receiver. When the cartridge is to be removed, the slot in its heel is disposed over the flanges at the forward end of the carriage so that a movement of the carriage away from the links will withdraw the cartridge therefrom, thus releasing the links and separating the belt of cartridges. A spring is provided about the pivot of the lever to urge the lever away from the handle portion of the receiver into position of operation.

Accordingly, the main objects of this invention

are: to provide a re-arming tool which operates to connect or disconnect a belt of cartridges through the movement of a lever in the same direction; to form a channel-shaped receiver from a stamping having a downwardly extending handle on one end and upwardly extending prongs on the other, with a carriage operated by a link and lever which move the carriage in forward and retracted position by a movement of the lever in the same direction; to form a re-arming tool with a forwardly and rearwardly movable carriage which is connected by a link to a point above or below its pivot point to produce the movement of the carriage in either direction by the same movement of the lever; to provide a re-arming tool having a receiver and an axially movable carriage with a lever which is interconnected by a link to the carriage and which is movable on a lever to a carriage advancing or retarding position by a bell crank which retains the links in either of the said positions; and, in general, to construct a re-arming tool from stampings which is simple in construction, positive in operation, and economical of manufacture.

Other objects and features of novelty of this invention will be specifically pointed out or will become apparent when referring, for a better understanding of the invention, to the following description, taken in conjunction with the accompanying drawings, wherein:

Fig. 1 is a plan view of a re-arming tool embodying features of the present invention;

Fig. 2 is a view in elevation of the tool illustrated in Fig. 1;

Fig. 3 is an end view of the structure illustrated in Figs. 1 and 2 as viewed from the left-hand end thereof;

Fig. 4 is a view of the structure illustrated in Fig. 2 when advanced to move the cartridge in belt-connected position;

Fig. 5 is a view of structure similar to that illustrated in Fig. 2, with the pivot of the link moved below the receiver for withdrawing a cartridge from the belt;

Fig. 6 is a plan view of structure, similar to that illustrated in Fig. 1, showing a further form which the invention may assume;

Fig. 7 is a view in elevation of the structure illustrated in Fig. 6;

Fig. 8 is an end view of the structure illustrated in Figs. 6 and 7 as viewed from the left-hand end thereof; and

Fig. 9 is a broken sectional view of structure,

similar to that illustrated in Fig. 2, showing a modified form thereof.

The re-arming tool embodies a receiver 10 which is made from a channel-shaped stamping having a web portion 11 and flange portions 12 and 13 extending upwardly at the sides. Toward the front of the web a pair of spaced prongs 14 extend upwardly in position to engage the end of the annular portion 15 of a connecting link 16 which, with the cartridges, make up the belt. A forward pair of upwardly extending spaced prongs 17 are closer than the prongs 14 for engaging the smaller annular portion 18 of the link 16 so as to prevent the nested links from moving forwardly or backwardly in the receiver when supported thereby between the prongs. The flanged portions 19 at the rear end of the tool are disposed closer together and terminate in a downwardly extending tubular handle portion 21.

A carriage 22 is mounted in the central part of the receiver between the flange portions 12 and 13 having a web portion 23 which is attached by a headed rivet 24 to the web 11 of the receiver in the slot 25 thereof. This retains the carriage within the receiver while permitting limited longitudinal movement therein. The carriage has a pair of side flanges 26 having the forward portions thereof bent inwardly at 27 for engaging the ends of the cartridges to either push or pull the cartridge relative to the nested links 16. The projecting portions of the flange abut against the end of the cartridge when pushing the cartridge forwardly and project within a slot 28 adjacent to the cartridge end when pulling the cartridge from the clip.

An operating lever 29 is secured to the receiver on the pivot 31 about which a spring 32 is supported for moving the lever 29 away from the handle portion 21 of the receiver. A slot 31 is provided in the lever which extends above and below the receiver terminating in the notches 34 and 35 at the ends. A link 36 is supported by the pivot 37 between the flanges 26 of the carriage 22, the other end of which is attached to a pivot 38 which slides within the slot 33 of the operating lever 29. The link 36 has flanges 41 at the top and bottom enlarged portion bearing serrations on the outer surface by which the link 36 is manipulated to have the pivot 38 moved from one to the other of the notches 34 and 35.

A spring 42 has one end anchored to a flange 26 of the carriage 22 and the other end secured to a tab 43 struck from the link 36. The spring 42 moves from one toggle position to another when the link 36 is adjusted from one to the other notch 34 or 35 for retaining the pivot 38 in the notch to which it is moved. When the link has its pivot 38 in the upper notch 34, a pull on the lever 28 towards the handle portion 21 will move the carriage 22 forwardly to push the cartridge into the clips. When the link 36 has the pivot 38 shifted to engage the notch 35 below the receiver, a pull upon the lever 29 will move the carriage 22 in the opposite direction away from the clips to withdraw the cartridge therefrom.

When the belt is to be built up or joined to another belt, the clips 16 are nested together between the prongs 14 and 17, as illustrated in the figure, with the cartridge partly inserted therethrough. With the pivot 38 in the upper notch 34, a pull on the lever 29 toward the handle portion 21 pushes the cartridge forward until the front and rear ends are aligned with the adjacent cartridges to add a cartridge to the belt or to join two belts together.

When a belt is to be separated, the links 16 are inserted between the prongs 14 and 17, the pivot 38 is shifted to the lower notch 35 and the inwardly projecting flanges 27 engage the notch 28 of the cartridge. A pull upon the lever 29 toward the handle portion 21 withdraws the cartridge from the clip, thereby separating the clips and the belt.

Figure 4 illustrates the tool in operated position with the cartridge pushed forward to join the belts or to add a cartridge thereto. Figure 5 illustrates the tool with the link 36 shifted to have the pivot 38 engage the notch 35 and the notch 28 of the cartridge nested in the flange portions 27 of the carriage. In this position a pull on the lever 29 toward the handle portion 21 withdraws the cartridge from the clips.

Referring to Figs. 6, 7, and 8, a slightly modified form of re-arming tool is illustrated. A link 51 is substituted for the link 36 and a pivot pin 52 is substituted for the pivot 38. The pivot pin 52 extends through an aperture 53 of a bell crank 54 which is pivoted on the pivot pin 31. The bell crank has a projecting lug 55 which engages one or the other of the depressions 56 and 57 in the lever 29 for retaining the bell crank 54 in either position relative to the lever 29. In the position illustrated, the bell crank 54 has moved and retains the pivot pin 52 in the position above the receiver for producing a forward movement to the carriage 22 when the lever 29 is moved toward the handle portion 21. The bell crank may be manipulated by the operating handle portion 58 to move the pivot 52 downwardly through a slot 59. The pivot is retained at the lower end of the slot by the engagement of the projecting lug 55 with the depression 57 of the lever 29. A movement of the lever 29 toward the handle portion 21 of the receiver moves the carriage 22 toward the end of the receiver containing the handle portion 21 for withdrawing the cartridge from the clip. It is only necessary to manipulate the handle portion 58 of the bell crank 54 to change the tool from one which withdraws the cartridge to one which inserts the cartridge, or vice versa. The pivot 52 is positively retained at one or the other end of the slot 59 through the engagement of the boss 55 of the bell crank with one of the depressions 56 and 57 in the lever 29.

Fig. 9 illustrates a slightly different form of structure for retaining the link at one or the other end of the slot 33 of the tool illustrated in Figs. 1 to 5, inclusive. In these figures, a coil spring 42 was employed which functioned as a toggle for holding the end of the link at one or the other end of the slot, depending upon whether a cartridge was to be inserted or removed. In Fig. 9 a link 61 is employed which is similar to the link 36 of the above-mentioned figures, but differing therefrom in having flat surfaces 62 and 63 provided on the end thereof. A flat spring 64 engages one or the other of the surfaces 62 or 63 for retaining the end of the link in its upper or lower position. Preferably, the slope of the surface is such as to produce a force on the link which tends to urge the pin 38 beyond the ends of the slot so that the pin will rest against the one or the other end of the slots at all times. The link may be supported in the carriage on the rivet 24 and may be prevented from turning on the pivot by a struck-out projection 65.

The tool is entirely self-contained and may be employed in building up, or removing, cartridges from a belt or for connecting or disconnecting

belt portions. The tool is rugged, yet simple in manufacture in view of the fact that all of the parts are made of stampings which require a minimum amount of labor and material, thereby materially reducing the cost of the tool.

What is claimed is:

1. A force applying tool including, in combination, a receiver embodying a channel portion and a handle portion extending downwardly from the channel portion, a lever pivoted to said receiver and disposed adjacent to said handle portion, a carriage in the channel portion of said receiver movable longitudinally therein, and a link interconnecting the carriage and lever which is shiftable to one of two positions for moving said carriage in either direction by a movement of the lever toward said handle.

2. A force applying tool including, in combination, a receiver embodying a channel portion and a handle portion extending downwardly therefrom, a lever pivoted to said receiver and disposed adjacent to said handle portion, a longitudinally movable carriage in the channel portion of said receiver, and a link interconnecting the carriage and lever for moving said carriage, said link being movable to a position of operation above and below said receiver for moving said carriage selectively in either direction with a movement of the lever toward said handle portion.

3. A re-arming tool including, in combination, a receiver having a clip-engaging portion at one end and a handle at the opposite end, a lever pivoted to said receiver, a carriage in said receiver movable longitudinally therein, said lever having a slot terminating above and below said receiver, and a link connected to said carriage and the slot in said lever.

4. A re-arming tool including, in combination, a receiver having a clip-engaging portion at one end and a handle at the opposite end, a lever pivoted to said receiver, a longitudinally movable carriage in said receiver, said lever having a slot terminating above and below said receiver, a link connected to said carriage and the slot in said lever, and a spring for moving said lever away from said handle.

5. A re-arming tool including, in combination, a receiver having a clip-engaging portion at one end and a handle at the opposite end, a lever pivoted to said receiver and having a slot which terminates above and below the pivoted point of said lever, a carriage in said receiver having inwardly projecting aligned flanges on the end adjacent to said clip-receiving portion, and a link connected to said carriage and the slot in said lever.

6. A re-arming tool including, in combination, a receiver having a clip-engaging portion at one end and a handle portion at the opposite end, a lever pivoted to said receiver and having a slot which terminates above and below the pivoted point of said lever, a carriage in said receiver having inwardly projecting aligned flanges on the end adjacent to said clip-receiving portion, and a link connected to the carriage and the slot in said lever, and a spring for retaining said link at one or the other end of said slot.

7. A re-arming tool including, in combination, a receiver having a clip-engaging portion at one end and a handle portion at the opposite end, a lever pivoted to said receiver and having a slot which terminates above and below the pivoted point of said lever, a carriage in said receiver having inwardly projecting aligned flanges on the end adjacent to said clip-receiving portion, a link interconnecting the carriage and the slot in said lever, a spring for retaining said link at one or the other end of said slot, and a spring for moving said lever away from said handle portion.
8. A re-arming tool including, in combination, a receiver having a clip-engaging portion at one end and a handle portion at the opposite end, a lever pivoted to said receiver, a carriage in said receiver having inwardly projecting aligned flanges on the end adjacent to said clip-receiving portion, and a link interconnecting the carriage and said lever, said link being movable to two different positions relative to said lever for moving said carriage in opposite directions when the lever is moved in the same direction.
9. A re-arming tool including, in combination, a receiver having a clip-engaging portion at one end and a handle portion at the opposite end, a lever pivoted to said receiver, a carriage in said receiver having inwardly projecting aligned flanges on the end adjacent to said clip-receiving portion, a link interconnecting the carriage and said lever, and an additional lever for moving and retaining the point of connection of said link with said first lever above or below the pivot thereof.
10. A re-arming tool including, in combination, a receiver having a clip-engaging portion at one end and a handle portion at the opposite end, a lever pivoted to said receiver, a carriage in said receiver having a cartridge-engaging flange on the end adjacent to said clip-receiving portion, a link interconnecting the carriage and said lever, and means for selectively retaining the end of the link connected to the lever at a point above or below the pivot thereof.
11. In a re-arming tool, a pair of elements which are pivoted together, means on one element for engaging and supporting a clip to be joined with a cartridge, and means operated by the other element for selectively moving the cartridge into and out of the clip.
12. A force applying tool including, in combination, a frame comprising a body portion and a handle portion extending downwardly therefrom, a lever pivoted to said frame and extending downwardly adjacent to said handle portion, a movable element in said frame which is movable longitudinally therein, and a link interconnecting the element and lever which is shiftable on said lever to pivot points above and below the pivot point of the lever for moving said element in either direction by the movement of the lever toward the handle depending upon the pivoted position of the link relative to the lever.

ALFRED H. HABERSTUMP.
